(57) **CLAIM**

The ornamental design for a control panel for a musical instrument, as shown and described.

DESCRIPTION

FIG. 1 is a top and right side perspective view of the control panel for a musical instrument, showing my new design;

FIG. 2 is a top plan view thereof;

FIG. 3 is a left side elevation view thereof;

FIG. 4 is a right side elevation view thereof;

FIG. 5 is a rear elevation view thereof;

FIG. 6 is a front elevation view thereof; and,

FIG. 7 is a perspective view of the control panel for the musical instrument, shown mounted on a guitar illustrated as environment in broken lines.

The broken lines are included in FIG. 7 for the purpose of illustrating environment of the control panel for a musical instrument that forms no part of the claimed design.

1 Claim, 5 Drawing Sheets
